CLAIM

The ornamental design for a bartender's shirt, as shown and described.

DESCRIPTION

FIG. 1 is a prospective view of the bartender's shirt with sleeve pocket showing a multi-channel pocket on the upper left sleeve, which may be used to hold bartender's tools.

FIG. 2 is a front view of the bartender's shirt, showing a button-down shirt with a collar and cuffs and the multi-channel pocket on the front of the upper left sleeve.

FIG. 3 is a back view of the shirt shown in FIG. 2.

FIG. 4 is a left side view of the bartender's shirt showing the pocket on the front and left side of the upper left sleeve. In FIG. 4 the pocket contains exemplary bartenders' tools which are illustrated by broken lines.

FIG. 5 is a right-side view of the bartender's shirt.

FIG. 6 is a top view of the bartender's shirt shown in FIG. 4. In FIGS. 4 and 6 the pocket contains exemplary bartenders' tools.

FIG. 7 is a bottom view of the bartender's shirt.

FIG. 8 is a close up view of the pocket and individual channels which may be used to hold bartender's tools. In FIGS. 8, 9, 10, 11, and 12, the pocket does not contain exemplary bartenders' tools.

FIG. 9 is a top view of the pocket in FIG. 8.

FIG. 10 is a bottom view of the pocket in FIG. 8.

FIG. 11 is a front view of the pocket in FIG. 8.

FIG. 12 is a back view of the pocket in FIG. 8; and,

FIG. 13 is a front view of an alternative embodiment of the bartender's shirt which may be buttoned from the opposite side.

In FIGS. 1-13, broken lines represent unclaimed subject matter. The fine broken lines represent stitching. Neither type of broken line forms any part of the claimed design and are for illustrative purposes only. In FIGS. 1, and 4-7, the shirt is illustrated as if on a human figure. For clarity the human figure is not shown. In FIGS. 2, 3, and 13, the shirt as illustrated is not on a figure. In FIGS. 1, 4, and 6, exemplary bartender's tools are shown protruding from the pocket, as represented by broken lines. In FIGS. 2 and 8-13, no exemplary bartender's tools are shown to be present in the pocket.

1 Claim, 10 Drawing Sheets
